US00D767409S

(12) United States Design Patent (10) Patent No.: US D767,409 S
Nickell (45) Date of Patent: * Sep. 27, 2016

(54) TRAY

(71) Applicant: ASCLEMED USA, INC., Torrance, CA (US)
(72) Inventor: Robert P Nickell, Torrance, CA (US)
() Term: 14 Years
(21) Appl. No.: 29/522,870
(22) Filed: Apr. 2, 2015
(51) LOC (10) Cl. 09-03
(52) U.S. Cl. D9/737
USPC ....
